UNITED STATES PATENT OFFICE.

FLORA SCHAFFER, OF TERRE HAUTE, INDIANA.

FOLDING CAMPING OUTFIT.

1,283,322.

Specification of Letters Patent.

Patented Oct. 29, 1918.

Application filed April 8, 1918. Serial No. 227,302.

To all whom it may concern:

Be it known that I, FLORA SCHAFFER, a citizen of the United States, residing at Terre Haute, in the county of Vigo and State of Indiana, have invented a new and useful Folding Camping Outfit, of which the following is a specification.

It is the object of this invention to provide a structure including benches, a table therebetween, and a canopy shielding the table and the benches, the device being so constructed that it can be folded up into small compass when not in use, the structure being of peculiar utility on camping excursions, at picnics, and elsewhere.

It is within the province of the disclosure to improve generally and to enhance the utility of devices of that sort to which the invention appertains.

Changes such as a mechanic might make may be resorted to, within the scope of what is claimed, without departing from the spirit of the invention.

In the accompanying drawings:—

Figure 1 shows in side elevation, a folding camping outfit constructed in accordance with the invention, parts being broken away; Fig. 2 is a horizontal section taken approximately on the line 2—2 of Fig. 1; Fig. 3 is a vertical section thereof; and Fig. 4 is a sectional view taken through the upper part of the canopy, portions appearing in elevation.

In carrying out the invention there is provided a pair of benches 1 and 2, each including a seat 3 having cleats 4 to which the upper ends of the inner legs 5 and the outer legs 6 are pivoted, by means of clamp screws 7, or in any other suitable manner. The outer legs 6 of each bench are connected by a cross bar 8. The legs 5 carry pivot elements 9, which may be clamp screws, engaged with inclined braces 10 having notches 11 adapted to coact with the clamp screws 12 carried by the outer legs 6. The invention comprises parallel sills 14 and each sill 14 includes a long section 15 and a short section 16, the sections 15 and 16 being united by means of hinges 17, so that the sills can be folded vertically.

The numeral 18 denotes generally, a table including a top 19 carrying cleats 20. In the ends of the top 19, above the cleats 20 notches 21 are formed, there being keepers 22 secured to the cleats 20 below the notches 21. Legs 23 and 24 are provided, the upper ends of the legs being attached by means of

pivot elements 25, such as set screws, to the cleats 20. The numeral 26 marks braces pivotally united at the lower end, by means of clamp screw 27, with legs 23, the braces 26 having notches 50 receiving clamp screws 28 carried by the legs 24, the braces 26 being inclined between the clamp screws 28 and the clamp screws 27.

By means of the clamp screws 29, the legs 5 and 6 of the bench 1 are attached to the sections 15 of the sills 14, the legs 5 and 6 of the bench 2 being attached in a like manner to the members 16, the legs 23 and 24 of the table being attached in a like way to the part 15, the table being disposed between the benches, as shown in Figs. 1 and 3.

The structure includes a canopy 30 comprising uprights 31 extended downwardly through the notches 21 in the table top 19 and through the keepers 22, the uprights having reduced ends 32 received in the keepers 33 attached to the sections 15 of the sills 14, the reduced ends of the uprights forming shoulders 34 therein, which, coöperating with the keepers 33, prevent the uprights from sliding downwardly. A horizontal top bar 35 is disposed between the upper ends of the uprights 31. Pins 36 are provided, the inner ends of the pins being threaded at 37 into the ends of the top bar 35, the pins carrying abutment plates 38 which engage the end of the bar 35.

The pins 36 pass through the upper ends of the uprights 31 as shown in Fig. 4. Inclined rafters 39 are provided, the upper ends of the rafters being mounted on the pins 36, on the opposite sides of the uprights 31. Wing nuts 40 are threaded on the ends of the pins 36 and serve to hold the top bar 35, the rafters 39 and the uprights 31 together in a way which will be understood readily from Fig. 4.

Braces 41 are provided, the lower ends of the braces being mounted on clamp screws 42 carried by the uprights 31. The upper ends of the braces 41 are fastened by means of clamp screws 43 to the inclined rafters 39. Rollers 44 are disposed between the ends of the rafters 39 and carry pins 45 constructed like the pins 36. Wing nuts 57 are threaded on the pins 45 and engage the rafters 39 to hold them on the ends of the rollers 44. The flexible cover 47 made of cloth or of any water proof material extends across the top bar 35 and is supported on the rafters 39, the cover being secured as shown at

48 to the rollers 44. The cover 47 has a depending edge 49 which extends downwardly below the rafters 39, and below the rollers 40.

5 The utility of the structure will be seen without difficulty when Figs. 1 and 3 are noted. A person sitting on either of the benches 1 or 2 may use the table 18, the canopy 30 extending above both the benches and 10 the table.

One of the main advantages of the device is that it can be collapsed and folded into small compass for shipment, for transportation on an automobile, or for a similar 15 purpose. Thus, the braces 10 can be detached from the legs 6 of the benches 1 and 2, the legs 5 and 6 being folded with respect to the sills 14 on the corresponding pivot members 29. Further, the constituent parts 20 15 and 16 of the sill 14 can be folded on the hinges 17. The uprights 31 of the canopy 30 may be drawn upwardly out of the keepers 22 and 33, and when the braces 26 are detached from the legs 24 of the table, the 25 table can be folded down so as to occupy but

little space. The braces 41 may be detached from the rafters 39 or from the uprights 31, thereby permitting the rafters 39 to be folded together, one or both of the rollers 44 being rotated to wind the cover 47 thereon, the 30 uprights 31 being swung on the pin 36 into substantial alinement with the folded rafters 39.

Having thus described the invention, what is claimed is:—

In a device of the class described, sills comprising relatively foldable parts; hinges connecting said parts; a table including legs pivoted to one of said parts; a bench adjacent the table and comprising legs pivoted 40 to the other of said parts; and means for holding the legs against movement with respect to the sills.

In testimony that I claim the foregoing as my own, I have hereto affixed my signature in the presence of two witnesses.

FLORA SCHAHFER.
